UNITED STATES PATENT OFFICE.

MORTIMER D. STEDMAN, OF UNIONVILLE, CONNECTICUT, ASSIGNOR TO
CHARLES C. DUNHAM, OF SAME PLACE.

CONVEYER FOR NUT-MACHINES.

SPECIFICATION forming part of Letters Patent No. 292,870, dated February 12, 1884.

Application filed May 12, 1883. (No model.)

To all whom it may concern:

Be it known that I, MORTIMER D. STEDMAN, a citizen of the United States, residing at Unionville, in the county of Hartford and State of Connecticut, have invented certain new and useful Improvements in Conveyers for Nut-Machines, of which the following is a specification.

My invention relates to improvements in 10 conveyers or transmitters in a nut-machine for carrying the nut, after it is blanked out, to the punching and hammering mechanism; and the objects of my invention are to do this work in a simple and efficient manner, and so that the blank shall be accurately and positively seated 15 in its proper position within the hammering-dies. I attain these objects by means of the mechanism illustrated in the accompanying drawings, in which—

20 Figure 1 is a plan view of my conveyer and its operating mechanism, together with a sketch of the hammering mechanism in proper relative position thereto, the same being shown with the conveyer in that position in which it is found when it receives the nut-blank from the shears or punching-dies. Fig. 2 is a like view of the same parts with the conveyer in the position in which it is found immediately after depositing the nut-blank in the hammering mechanism. Fig. 3 is a side elevation of 25 my conveyer; and Fig. 4 is another elevation of the same, looking toward the end of the conveyer-arms.

30 *a a* designate the movable hammers, and *b b* designate the anvils of the hammering mechanism. These are arranged over a suitable bed in any well-known manner, except that one of the hammers is represented as curved instead of straight; but this feature is not intended to be incorporated in this application. For the purposes of my invention it is only necessary that one of the hammers shall have such a movement that when it retreats it will be out of the way of the conveyer. Extending 35 through the same bed of the machine upon which the hammering mechanism is placed I arrange the shaft A by the side of said hammering mechanism. Upon the lower end of this shaft and under the bed I arrange the pinion B, and by the side of the same, and

meshing into the teeth thereof, a reciprocating rack, C. Upon the upper end of the shaft, and rigidly secured so as to rotate therewith, I arrange the arm D of my conveyer. Upon the same shaft I arrange another arm, e, which is loosely mounted upon the shaft, so that it can vibrate freely within certain limits independently of the shaft. The extent of this swinging movement is limited by means of the ledge d upon the end of the arched arm e. The outer end of the arm e is provided with a table for receiving the nut-blank, and upon either side thereof are the pivoted jaws f f, having an overhanging upper edge, as most clearly shown in Fig. 3. A small spring, g, Fig. 3, is placed between the lower ends of these jaws, to press their upper ends inward continually. As shown, these jaws and the table between them are made of sufficient length to receive the nut-blank h, although said jaws may not be stopped directly under the punching-die, or in case the nut-blank should not fall squarely upon them as it is fed from said die. The nut-blank is pushed down from the shear or blanking-dies into and between the jaws with sufficient force to overcome the power of the spring and open the jaws. As soon as the nut-blank passes the overhanging upper edges of the jaws, they snap together again. After the nut-blank has been thus deposited within said jaws, as shown in Fig. 1, the rack C moves in one direction to carry the arms e and D around into the position shown in Fig. 2. In moving into this position the parts move together, as shown in Fig. 1, until the forward ends of the jaws f f come in contact with the hammering mechanism. The movement of the arm e is arrested by said contact; but the movement of the arm D continues for a while longer, thereby carrying the end of the knock-out arm k in between the jaws f f and up against the hammering mechanism, thereby pushing the nut out from between the jaws into position to be hammered, as shown in Fig. 2. The rack C then moves in the opposite direction, to carry the parts back to their former position. Just before the rack C completes its stroke, the arm e comes in contact with the stop m, or other suitable stop upon the bed of the machine, and arrests the motion of the arm e until the arm D 100

has been withdrawn therefrom, as shown in Fig. 1.

I claim as my invention—

1. The combination of the conveyer-arm D, having knock-out *k*, said arm being rigidly secured to its driving-shaft, the arm *c*, carrying holding-jaws and loosely mounted on the same driving-shaft, and mechanism for oscillating the shaft upon which said arms are mounted, substantially as described, and for the purpose specified.

2. In a conveyer, the combination of the pivoted jaws *f*, the table between said jaws, the knock-out arm *k*, and their operating mechanism, substantially as described, and for the purpose specified.

3. The combination of the conveyer, the holding-jaws, the knock-out, and mechanism for swinging the conveyer back and forth from and to the hammering-dies, substantially as described, and for the purpose specified.

4. The combination of the conveyer-arm D, having knock-out *k*, the arm *c*, bearing holding-jaws and loosely mounted upon the driving-shaft, and devices for limiting the extent of the swinging movement of the arm *c*, substantially as described, and for the purpose specified.

MORTIMER D. STEDMAN.
